BUFFER MECHANISM FOR FIREARMS

Clarence E. Simpson, Springfield, Mass., assignor
to the United States of America as represented
by the Secretary of War

Application April 8, 1947, Serial No. 740,035

5 Claims. (Cl. 89—1)

(Granted under the act of March 3, 1883, as
amended April 30, 1928; 370 O. G. 757)

1

The invention described in the following specification and claims may be manufactured and used by or for the Government for governmental purposes without the payment to me of any royalty thereon.

This invention relates to a buffer mechanism for automatic firearms, more particularly to firearms having a heavy breech block with correspondingly large recoil energy.

The various buffer mechanisms of nearly all firearms rely largely upon spring means to absorb the recoil energy of the reciprocating breech member. While such mechanisms do absorb the recoil energy fairly satisfactorily, such mechanisms have the disadvantage of imparting a rebound to the reciprocating breech member. This rebound is objectionable for the reason that the timing of the firearm is upset with resulting failures to feed and other difficulties.

Those buffer mechanisms which do not employ spring means to absorb the recoil energy of the reciprocating breech member frequently utilize a stack of disks of some relatively resilient material, such as fiber. The main drawback with such buffer mechanisms, however, is their inability to gradually absorb the recoil energy when the breech block strikes such a buffer. Although the material contained in the stack of disks does have some resiliency, it is relatively slight so that the effect of the breech block striking such a buffer is about the same as if striking a solid object. Hence a severe shock is applied to the firearm when the rearward travel of the breech block is suddenly arrested. There is a further disadvantage in that the breech block member rebounds after impact with such a buffer which affects the timing and feeding of the firearm.

Accordingly, it is an object of this invention to provide a buffer mechanism for a firearm wherein the recoil energy of the reciprocating breech member of the firearm is gradually absorbed so as to substantially eliminate any rebound of the breech block from the buffer mechanism.

A particular object of this invention is to provide a buffer mechanism for a firearm such as disclosed in my copending application for Firearm, Serial No. 675,124, filed June 7, 1946.

The specific nature of the invention as well as other objects and advantages thereof will clearly appear from a description of a preferred embodiment as shown in the accompanying drawings in which:

Fig. 1 is an enlarged partial side elevational view of a firearm shown in longitudinal section

illustrating the elements of the buffer mechanism of this invention;

Fig. 2 is a perspective view of the buffer sleeve;

Fig. 3 is a top view of the buffer mechanism housing, shown positioned in the rear of a firearm receiver;

Fig. 4 is an enlarged detail side elevational view of the outer telescoping tube having a conically shaped end; and

Fig. 5 is a side elevational view of the inner telescoping tube.

This invention essentially comprises a housing adapted to slidably contain two telescoping tubes. The innermost of such tubes contains a spring. Conical shoulders are provided on each of the telescoping tubes which abut a sleeve having correspondingly shaped sides. The recoil energy of the reciprocating member of the firearm is absorbed by the buffer mechanism when such member strikes the tube projecting forwardly from the housing. Such force telescopes the two tubes by expanding the buffer sleeve placed between the two conical shoulders of the telescoping tubes thereby dissipating the recoil energy against the bore of the housing. The spring contained within the inner telescoping tube acts to return the mechanism forwardly to its normal location when the breech block starts toward battery position.

There is shown in Fig. 1 a portion of a firearm including the buffer mechanism which embodies this invention. The elements of the buffer mechanism are contained within a housing 10 secured to the rear end of a firearm receiver 11. Housing 10 comprises a substantially rectangular block portion 14 which has formed thereon an integral rearwardly projecting, cylindrical boss 12. The rectangular portion 14 of housing 10 serves as a rear spacer for receiver 11 to which are secured the side plates of such receiver. An axial bore 13 is provided in boss 12 which passes through the block portion 14 of housing 10, such bore being of reduced diameter as shown at 15 when it emerges from the forward face of block 14. Boss 12 is provided with threads 16 on the outer periphery thereof to receive a buffer cap 17, such buffer cap retains the buffer mechanism within bore 13 as will be later described.

The buffer mechanism comprises mainly two telescoping tubes 18 and 19. Each of such tubes is provided with a closed end as shown at 20 and 21 of tubes 18 and 19 respectively. The closed end 21 of tube 19 is of reduced diameter so as to project forwardly through reduced diameter portion 15 of bore 13, such reduced diameter portion 55 of tube 19 forming a shoulder 22 which limits the

amount of protrusion of tube 19 from housing 10. The open end of tube 19 is conically shaped as shown at 23 for a purpose to appear presently.

Tube 19 is slidably contained within bore 13 of housing 10. Tube 18 is slidably contained within tube 19 and the open end of such tube has an enlarged conically shaped head portion 24. When tube 18 is positioned within tube 19, the conically shaped head portion 24 is disposed rearwardly within housing 10.

A buffer sleeve 25 is placed about tube 18. Such buffer sleeve has inwardly tapered ends 26 having a taper corresponding to that of conical head 24 of tube 18 and conically shaped end 23 of tube 19. Thus when sleeve 25 surrounds tube 18 the inwardly sloped end 26 of such sleeve cooperates with conical head portion 24 of tube 18, while the opposite similarly tapered end 26 of sleeve 25 cooperates with conical end 23 of tube 19, to provide a wedging or camming action as will be later described.

The sleeve 25 is preferably made from a material having a low coefficient of friction such as a bronze alloy and such sleeve is preferably split to permit greater expansion thereof.

A buffer spring 28 is inserted within tube 18, one end being in abutting relationship with the closed end 20 of such tube, while the other end of spring 28 abuts the inside face of cap 17 to retain such spring within tube 18. Spring 28 is centrally positioned against cap 17 by a stud 29 axially secured on the inside face of such cap. Spring 28 acting against the closed end of tube 18 forces the entire buffer mechanism forwardly so that shoulder 22 of tube 19 abuts a corresponding shoulder 31 provided on the inside of housing 10 formed by the reduced diameter portion 15 of bore 13.

A breech block 30 is slidably contained within receiver 11 and such breech block is returned to battery position by the operating or driving springs (not shown). When a cartridge is discharged in the firearm, breech block 30 is driven rearwardly with considerable force and such energy as is not absorbed by other recoil checking means is absorbed by the buffer mechanism contained within housing 10. When the rear end of breech block 30 strikes the forwardly disposed closed end 21 of tube 19, such tube is driven rearwardly. The conical end 23 of tube 19 being in engagement with the inwardly sloped end 26 of sleeve 25 forces such sleeve and tube 18 rearwardly at the same time expanding sleeve 25 and then compressing spring 28. However as the buffer mechanism is forced rearwardly, the component of the rearward force is directed largely to the bore of housing 10. Spring 28 biasing tube 18 forwardly resists the rearward movement of sleeve 25 thereby assisting the expansion of sleeve 25. Therefore the rearward force of breech block 30 is dissipated in friction against the walls of housing 10. The expansion of sleeve 25 increases the frictional force against the bore of housing 10 in its rearward movement thereby completely absorbing the recoil energy of breech block 30 in the short distance of travel permitted by the buffer mechanism.

When the recoil force of breech block 30 is completely absorbed, the telescoping tubes 18 and 19 are in a collapsed or fully telescoped position and remain so until the operating spring (not shown) starts return of the breech block to battery position whereupon the tubes separate by action of spring 28. Such spring forces tubes

18 and 19, including sleeve 25, forwardly until shoulder 22 strikes a corresponding shoulder 31 within housing 10 thus positioning the buffer mechanism for receiving the impact of the breech block of a successive recoil stroke.

From the foregoing description it is clearly apparent to those skilled in the art that there is here provided a buffer mechanism capable of receiving and dissipating the recoil energy of a reciprocating breech block without causing any objectionable rebound of the breech member. The buffer sleeve 25 is expanded against the bore of the buffer housing by tubes 18 and 19 and the whole buffer mechanism travels rearwardly. The expanded buffer sleeve holds the buffer spring under compression until such time as the breech member goes forwardly whereupon the buffer spring returns the buffer mechanism forwardly.

One of the unique features of this invention as previously pointed out, resides in the buffer mechanism being returned forwardly in a relatively gradual manner instead of being shot forwardly as is common with most buffer mechanisms. The engagement of buffer sleeve 25 with the bore of housing 10 is responsible for such slow return.

In practice the buffer mechanism herein described has reduced the forward velocity of the reciprocating breech member by as much as one-half that of conventional buffer mechanisms. Thus it is plainly obvious that improved timing and feeding can be achieved when utilizing the buffer mechanism of this invention. It is further pointed out that the buffer mechanism herein described is of simple and rugged construction lending itself to ease and rapidity of fabrication. Further such mechanism has a wide use in a variety of firearms but is principally employed in firearms having a reciprocating breech member of comparatively great weight and where the recoil energy of such member is correspondingly high.

I claim:

1. In a firearm having a reciprocating breech member, a buffer mechanism comprising, a housing, a pair of telescoping tubes slidably mounted in said housing and arranged for limited longitudinal movement, a split sleeve surrounding one of said tubes, said tube constructed to retain said sleeve thereon, said other tube abutting said sleeve, and resilient means maintaining one of said tubes in the path of the breech member to receive the impact thereof, said sleeve being constructed and arranged to transmit the force of impact of the breech member to said housing.

2. In a firearm having a reciprocating breech member, a buffer mechanism comprising, a housing secured to the firearm, said housing having a longitudinal bore therethrough, a stepped shoulder in said bore, a first tube having a closed end slidably mounted in said bore, said first tube constructed and arranged to abut said shoulder while said closed end projects forwardly out of said housing, a second tube having a closed end, said second tube being inserted in said first tube with said closed end adjacent said closed end of said first tube, a split sleeve surrounding said second tube and abutting the open end of said first tube, said second tube being constructed to retain said sleeve thereon, and resilient means for maintaining said first tube in the path of the breech member to receive the impact thereof, said sleeve being constructed and arranged to transmit the force of impact of the breech member to the bore of said housing.

3. In a firearm having a reciprocating breech member, a buffer mechanism comprising, a housing having a longitudinal bore therethrough, a stepped shoulder in said bore, a first tube having a closed end slidably mounted in said bore, said first tube constructed and arranged to abut said shoulder while said closed end projects forwardly out of said housing, said first tube having a conically chamfered open end, a second tube having a closed end, said second tube having an annular conical ring disposed about the open end thereof, said second tube being slidably mounted within said first tube with said closed end adjacent said closed end of said first tube, a split sleeve surrounding said second tube, said sleeve having an inwardly tapered edge on each end being engaged on one end by said conical end of said first tube and by said ring of said second tube on the other end thereof, and resilient means for maintaining said first tube in the path of the breech member to receive the impact thereof whereby said sleeve by expansion transmits the force of impact of the breech member to the bore of said housing.

4. In a firearm having a reciprocating breech member, a buffer mechanism comprising, a housing having a longitudinal bore therethrough, a stepped shoulder in said bore, a first tube having a closed end slidably mounted in said bore, said first tube constructed and arranged to abut said shoulder while said closed end projects forwardly out of said housing, said first tube having a conically chamfered open end, a second tube having a closed end, said second tube having an annular conical ring disposed about the open end thereof, said second tube being slidably mounted within said first tube with said closed end adjacent said closed end of said first tube, a split sleeve surrounding said second tube, said sleeve having an inwardly tapered edge on each end being engaged on one end by said conical end of said first tube and by said ring of said second tube on the other end thereof, and a helical spring in said second tube arranged to bias both of said tubes and said sleeve forwardly in position to receive

the impact of the breech member to permit expansion of said sleeve thereby transmitting the force of such impact to the bore of said housing.

5. In a firearm having a reciprocating breech member, a buffer mechanism comprising, a housing having a longitudinal bore therethrough, a stepped shoulder in said bore, a first tube having a closed end slidably mounted in said bore, said first tube constructed and arranged to abut said shoulder while said closed end projects forwardly out of said housing, said first tube having a conically chamfered open end, a second tube having a closed end, said second tube having an annular conical ring disposed about the open end thereof, said second tube being slidably mounted within said first tube with said closed end adjacent said closed end of said first tube, a split sleeve surrounding said second tube, said sleeve having an inwardly tapered edge on each end being engaged on one end by said conical end of said first tube and by said ring of said second tube on the other end thereof, a helical spring inserted in said second tube, a cap member secured to said housing to retain said spring in said second tube, said spring being provided to resist rearward movement of said sleeve on impact of the breech member with said closed end of said first tube to permit expansion of said sleeve to transmit the recoil energy of the breech member to the bore of said housing and to return said tubes and sleeve forwardly as the breech member returns to battery position.
